IRONING MACHINE SHOE COUPLING AND
EMERGENCY RELEASE MEANSFrederick M. Freis, Chicago, Ill., assignor, by
mesne assignments, to Conlon-Moore Corpora-
tion, Cicero, Ill., a corporation of Delaware

Application November 14, 1945, Serial No. 628,489

11 Claims. (Cl. 38—61)

1

This invention relates to ironing machines, particularly ironing machines intended for domestic or home use, and has to do with means for releasing the ironing shoe from the cooperating roll of the machine.

My invention is directed particularly to safety release means whereby the ironing shoe may quickly be released from the roll, for movement away therefrom, in case of emergency, this release means also serving normally to lock the shoe supporting arm to the shoe operating shaft for movement therewith to and from the roll. More specifically, my invention is directed to the provision of efficient shoe release means comprising but few parts and which is simple and positive in its operation, such release means being associated with shoe supporting means including spring means effective for urging the shoe toward the roll under yielding pressure during the ironing operation and for cushioning movement of the shoe rearward away from the roll upon release of the shoe from the shaft and rearward movement of the shoe by the release means. Further objects and advantages of my invention will appear from the detail description.

In the drawings:

Figure 1 is a back view of an ironing machine, with the shoe cover removed, embodying the shoe release means of my invention;

Figure 2 is a sectional view, on an enlarged scale, taken substantially on line 2—2 of Figure 1, with certain parts shown in elevation and the roll indicated in dot and dash lines;

Figure 3 is a sectional view, on an enlarged scale, taken substantially on line 3—3 of Figure 1, certain parts being shown in elevation;

Figure 4 is a front view of the shoe supporting arm and the release means and associated parts, taken substantially on line 4—4 of Figure 3;

Figure 5 is a sectional view, on an enlarged scale, taken substantially on line 5—5 of Figure 1, certain parts being shown in elevation;

Figure 6 is a view similar to Figure 5 but with the shoe released from the shoe operating shaft and moved away from the roll; and

Figure 7 is a view similar to Figure 6 but with the shoe moved to the roll and not coupled to the shoe operating shaft, the latter occupying the angular position which it assumes for moving the shoe into pressure contact with the roll.

I have shown the release means of my invention as applied to a portable ironing machine, such as that disclosed in my Patent No. 2,346,374, issued April 11, 1944, by way of example, it being understood, however, that my invention may also be applied to other ironing machines having a rockable shoe operating shaft or equivalent means for moving the shoe to and from the roll of the machine. The ironing machine comprises a base 7 having at one end an upwardly extending gear housing 8 from which extends a

rotatably mounted roll 9 and a rockably mounted shoe operating shaft 10, disposed in back of roll 9 adjacent the lower portion thereof and parallel therewith. The gear housing 8 contains suitable mechanism for rocking the shaft 10 in opposite directions and to predetermined extent, and also includes mechanism for rotating the roll, the machine being driven by a suitably located electric motor, this motor conveniently being housed within the roll as in my above identified patent. An ironing shoe 11, of known construction, is disposed in back of the roll 9 for cooperation therewith, and is moved to and from the roll in a manner which will be described presently. This shoe is provided with suitable heating means or resistor elements 12, of known type, mounted at the back of the face plate of shoe 11 and secured thereto by channel clamping bars 13 and 14, these bars being secured to the shoe by screw studs 15 welded or otherwise suitably secured to the face plate of shoe 11 and receiving nuts 16 seating against the outer faces of the bars.

The central clamping bar 14 is provided with a pair of ears 17 struck outward therefrom and disposed at the outer faces of forwardly extending ears 18, provided at the upper ends of side flanges 19 of a shoe supporting arm 20 of substantially U shape in cross section, the lower ends of flanges 19 being pivoted on the shoe operating shaft 10.

Each of the ears 18 is provided with a slot 21 extending in a direction forward and rearward thereof, that is, transversely to the shoe operating shaft 10. The slots 21 receive a pin 22 which passes through ears 17, this pin also passing through forwardly extending arms 23 of a U-shaped mounting bracket 24, the bight portion 25 of which seats against the front face of the upper end portion of a leaf spring 26. Bracket 24 is securely clamped to spring 26, by a clamp plate 27 seating against the back face of spring 26, and securing bolts 28 passing through bight portion 25 of bracket 24 and 45 through plate 27 and having nuts 29 threaded on their rearward ends, with lock washers 30 disposed between the nuts 29 and plate 27. As will be noted more clearly from Figure 4, spring 26 is of less width than plate 27 and bight portion 25 of bracket 24, and the bolts 28 are disposed in contact with the lateral edges of spring 26 so as to maintain bracket 24 and plate 27 in proper centered relation to the spring.

At its lower end spring 26 is secured, by a clamping plate 32, disposed at the front of spring 26, and cooperating screws 33, to back wall or bight portion 34 of shoe supporting arm 20. The screws 33 pass through wall 34, with lock washers 35 disposed between the heads of the respective screws and wall 34, and screws 33 are disposed in contact with the lateral edges of spring 26, as

shown more clearly in Figure 4, restraining spring 26 against transverse movement relative to wall 34. The spring 26 is rather thick or heavy so as to exert considerable spring pressure for holding the shoe to the roll, as will appear more fully presently, and the upper end of this spring has permanent pivotal connection to the shoe 11, through ears 17 thereof and arms 23 of bracket 24, the shoe having lost motion connection in a forward and rearward direction to the shoe supporting arm 20, through the slotted ears 18 of arm 20 and the pin 22 operating in the slots 21 of ears 18.

The shoe operating shaft 10 is turned a predetermined distance forward and a predetermined distance rearward, for moving the shoe to and from the roll, in the use of the machine, and in order that the shoe may partake of the movement of the shaft I provide latch means whereby the shoe supporting arm 20 may be locked to shaft 10 and, in emergency, may be released therefrom for independent movement away from the roll. A release lever 37, of substantially inverted U shape, is pivoted adjacent its lower end, on a pin 38 extending transversely of shoe supporting arm 20 and mounted at its ends in flanges 19 thereof. A latch finger 39, shaped as shown in Figure 3, is spot welded or otherwise suitably secured to the lower end portion of each arm 40 of release lever 37, the pivot pin 38 passing through the fingers 39 as well as through arms 40 to provide increased areas of bearing of lever 37 on pin 38. Each of the fingers 39 is provided with a downwardly opening notch 41 disposed to engage over the square head 42 of a stud 43 secured through shaft 10 diametrically thereof. As will be noted more clearly from Figure 4, the studs 43 are so disposed that the heads 42 thereof are in contact with the inner faces of flanges 19 of arm 20, or substantially so, effective for restraining this arm against relative movement lengthwise of the shoe operating shaft 10. A torsion spring 45 is wound about pin 38, at the inner face of one of the arms 40 of the lever 37, and has a forward upwardly extending arm 46 the upper end of which is hooked in back of and over a shouldered screw 47 which is threaded into the adjacent arm 40 of lever 37. Spring 45 is also provided with a rearward upwardly extending arm 48, the upper portion of which is in contact with the forward face of back wall 34 of shoe supporting arm 20. It will be seen that spring 45 urges release lever 37 in a counter-clockwise direction about pin 38, as viewed in Figure 3, thus urging the latch fingers 39 toward the shoe operating shaft 10. Pin 38 is restrained against lengthwise movement relative to arm 20 and lever 37, by cotter pins 49 passing therethrough adjacent spring 45 and the inner face of one of the fingers 39, pin 22 likewise being restrained against endwise movement by cotter pins 50 passing therethrough at the outer faces of ears 17 of clamping bar 14.

In the normal position of the release lever 37, shown in Figure 3, the notches 41 of latch fingers 39 receive heads 42 of studs 43, the heads 42 fitting snugly within notches 41 in contact with the forward and rearward walls thereof so as to avoid any looseness or play between fingers 39 and heads 42. In that manner the shoe supporting arm 20 is locked to shaft 10 for movement therewith so that when shaft 10 is turned a predetermined distance in counterclockwise direction, as viewed in Figure 3, the shoe 11 is moved into contact with roll 9, after which arm 20 moves a further distance with shaft 10 so as to place the spring 26 under

5 tension, whereby shoe 11 is maintained under spring pressure in contact with roll 9 or with articles being ironed and passing between the roll and the shoe, the pin 22 being then located at the rearward portions of slots 21, as shown in Figure 3.

When the shaft 10 is turned in clockwise direction, from its position shown in Figure 3, the upper end of arm 20 is moved rearward relative to shoe 11 as permitted by the slots 21, relaxing tension of spring 26, until the pin 22 contacts the ears 18 at the forward end of slot 21, at which time arm 20 picks up the shoe and moves it rearward away from roll 9 a distance predetermined by the extent of turning of shaft 10 in clockwise direction. The described movement of the shoe to and from the roll by turning of shaft 10 in opposite directions is the normal operation which occurs in ironing machines of this general type having a rockable shoe operating shaft, and need not be described in greater detail, it being noted, however, that the connections between the shoe and the shoe supporting arm and the spring 26 are novel and constitute important features of my invention.

25 It will be noted that the release lever 37 extends upwardly above shoe supporting arm 20 and has a block or handle 52, formed of any suitable heat insulating material, secured to its right portion 53 by screws 54, or in any other suitable manner. 30 The block 52 projects somewhat above shoe 11 so as to be readily accessible from in front of the roll 9. In the case of an emergency requiring quick release of the shoe from the roll, the operator forces the block 52 rearward, thereby swinging release lever 37 in clockwise direction, as viewed in Figures 3 and 5, about the pin 38. This rearward movement of lever 37 swings the fingers 39 upward and forward into the position shown in Figure 5, unlatching them from the heads 42 of studs 43, at which time arms 40 of lever 37 contact back wall 34 of shoe supporting arm 20, at the upper end of this wall. The arm 20 is then released from shaft 10, and in the continued rearward movement of lever 37, arm 20 swings 45 rearward about shaft 10, carrying with it the shoe 11, which is thus moved rearward away from roll 9. A cross pin 55 is carried by arm 20, in flanges 19 thereof, positioned below heads 42 of studs 43 and disposed for contact with heads 42 50 so as to limit the rearward movement of arm 20 about shaft 10. When arm 20 reaches its rearmost position, cross pin 55 is in contact with the underfaces of heads 42 of studs 43, as shown in Figure 6, the shoe 11 being then substantially in rear of the axis of shaft 10 and arm 20 being held in its rearmost position by gravity. Contact of pin 55 with heads 42 of studs 43 stops movement of arm 20 rather abruptly, and the shoe 11 tends to continue its rearward movement due to inertia. 55 The continued rearward movement of shoe 11 is cushioned by spring 26, the pin and slot connections between the shoe and arm 20 permitting of relative rearward movement of the shoe until such movement is overcome by spring 26, at which time the shoe is returned to the position shown in Figure 6, with pin 22 in contact with ears 18 at the forward end of slots 21. Spring 26 thus functions to cushion the rearward movement of shoe 11, upon release of arm 20 from shaft 10 and rearward movement of this arm in the manner described, while also serving to maintain the shoe in pressure contact with the roll or the articles being ironed, during the ironing operation, as above described.

60 After the supporting arm 20 has been released

from the shaft 10 and turns rearward thereabout in the manner above described, the release lever 37 is released and, under the influence of spring 45, assumes substantially the position shown in Figure 6, from which it will be noted that the forward portion of the respective latch fingers 39 is disposed for contact with the head 42 of corresponding stud 43. In order to again lock arm 20 to shaft 10, the handle or block 52 of release lever 37 is grasped by the operator and this lever is swung in a counterclockwise direction, carrying with it the supporting arm 20, during which movement the latch fingers 39 exert a camming action on heads 42 of studs 43 so that the lever 37 has slight turning movement in clockwise direction about pin 38, though the movement of lever 37 with arm 20 is in counterclockwise direction. In the continued counterclockwise movement of the arm 20 and lever 37 about shaft 10, the notches 41 of latch fingers 39 are brought into register with heads 42 of studs 43, at which time lever 37 is turned in counterclockwise direction, relative to arm 20, about pin 38, by springs 45, and the fingers 39 are engaged over heads 42 of studs 43 with a snap action. The shoe supporting arm 20 is then locked to shaft 10 for movement therewith, so as to move shoe 11 to and from roll 9 in the manner previously described. Preferably, after arm 20 has been released from shaft 10, this shaft is turned in clockwise direction, as viewed in Figures 5 and 6, into the position to which it is turned for moving the shoe away from the roll in the normal operation of the machine, it being understood that any suitable known means is provided for turning shaft 10 in opposite directions and to a predetermined extent, as previously stated. Turning of shaft 10 in clockwise direction, as stated, avoids contact of shoe 11 with roll 9 during the operation of reclutching or locking arm 20 to shaft 10 which obviously facilitates that operation. In Figure 6 the shaft 10 is shown in the angular position which it occupies when the shoe is in pressure contact with the roll, in the normal operation of the machine. It is to be noted, however, that the angular relation between shaft 10 and the shoe supporting arm 20, when this arm is in its released and rearmost position, is the same in either of the referred to angular positions of shaft 10, so that the operation of locking the arm 20 to shaft 10 would be the same in either case, with the exception that with shaft 10 in its angular position shown in Figure 6 the shoe 11 would be brought into pressure contact with roll 9 during the operation of locking arm 20 to shaft 10, which, while permissible in general, is not desirable since it interferes with the coupling operation. Since it is known in ironing machines to provide safety release means whereby the shoe may quickly be released from the shoe operating shaft, when in pressure contact with the roll, and to turn the shaft into the angular position which it occupies when the shoe is moved away from the roll in the normal operation of the machine, preliminary to again locking or clutching the shoe supporting arm to the shaft, it is not thought necessary to illustrate or describe that operation in greater detail. Suffice it to state that, in practice, shaft 10 is turned into its angular position which it occupies when the shoe has been moved away from the roll in the normal operation of the machine, preliminary to locking the shoe supporting arm 20 to shaft 10 after it has been released therefrom by operation of the emergency release lever 37.

While it is preferred to turn the shoe operating

shaft 10 in clockwise direction into its position in which the shoe 11 normally is away from the roll, preliminary to coupling shoe 11 to shaft 10, as above stated, that is not essential. If desired, the shoe 11 may be moved forward against the roll 9, but not in pressure contact therewith, by means of lever 37, while shaft 10 remains in the angular position which it occupies when holding shoe 11 in pressure contact with roll 9. The parts are then positioned as shown in Figure 7, with the shoe 11 in contact, but not pressure contact, with roll 9, and the latch fingers 39 cammed upward by heads 42 of studs 43 but not advanced sufficiently far forward to engage over heads 42. With the parts positioned as stated, the shaft 10 is turned clockwise into its position in which shoe 11 is away from roll 9. The lever 37 and the parts carried thereby remain in their forward positions of Figure 7, due to inertia and friction supplemented by the generally forward and upward pressure exerted on fingers 39 by heads 42 of studs 43, during the clockwise turning of shaft 10. As shaft 10 turns clockwise, fingers 39 are cammed further upward by heads 42 of studs 43, until heads 42 are aligned with notches 41. The fingers 39 then snap over heads 42, coupling the shoe 11 to shaft 10. In the continued turning of shaft 10 in clockwise direction, the shoe is moved therewith into its position away from roll 9, into which it is moved in the normal operation of the machine. On the succeeding operation of shaft 10, when it is turned in counterclockwise direction, shoe 11 is moved thereby into pressure contact with roll 9. In that manner, the coupling operation may be effected semi-automatically and with but slight effort on the part of the operator. Obviously, if desired, the lever 37 may be held manually in its forward position, though ordinarily that is not necessary.

As will be clear from what has been said, and from Figures 5, 6 and 7, the center of gravity of the shoe 11 and arm 20 and the parts carried thereby is so disposed that the shoe 11 will remain in either its position shown in Figure 6 or its position shown in Figures 5 and 7. That is advantageous in that it guards against unwanted movement of the shoe 11 toward the roll 9, when shoe 11 has been moved to its position of Figure 6, while permitting automatic coupling of arm 20 to shaft 10, by clockwise turning of the latter, when shoe 11 is against the roll 9 as in Figure 7. It is sometimes desirable, in adjusting an article to be ironed on the roll 9, to have the shoe 11 on light contact with the article, effective for holding it on the roll 9 while permitting the article to be adjusted and smoothed preliminary to ironing. After the article has been thus adjusted satisfactorily, shaft 10 is turned clockwise, coupling arm 20 to shaft 10 and is then turned counterclockwise for moving shoe 11 into pressure contact with the article for ironing the latter.

As has been above indicated, and as will be understood by those familiar with ironing machines of the general character herein disclosed, changes in construction and arrangement of parts of my invention may be resorted to without departing from the field and scope thereof, and I intend to include all such variations, as fall within the scope of the appended claims, in this application in which the preferred form only of my invention has been disclosed.

I claim:

1. In an ironing machine, a roll and a cooperating shoe, a rockably mounted shoe operating shaft in back of and parallel with said roll adja-

cent the lower portion thereof, a shoe supporting arm pivoted at its lower end on said shaft, a release lever pivoted on said arm, said lever and shaft having cooperating latching elements such that forward movement of said lever relative to said arm locks the latter to said shaft and rearward movement of said lever relative to said arm releases the latter from said shaft for rearward turning movement thereabout, said shaft and arm having cooperating abutments positively limiting rearward movement of said arm about said shaft, a leaf spring fixed at its lower end to said arm, and means providing permanent pivotal connection between the upper end of said spring and said shoe and forward and rearward lost motion connection between said shoe and the upper end of said arm, the latter having an abutment disposed for contact by said release lever in the movement thereof to releasing position.

2. In an ironing machine, a roll and a cooperating shoe, a rockably mounted shoe operating shaft in back of and parallel with said roll adjacent the lower portion thereof, a shoe supporting arm comprising side flanges pivoted at their lower ends on said shaft and a back wall connecting said flanges, latching studs fixed to said shaft projecting outward therefrom in proximity to said flanges restraining said arm against relative movement lengthwise of said shaft, a leaf spring fixed at its lower end to said back wall extending upward and forward therefrom, a release lever pivoted on said flanges extending upward above said arm and having latching fingers engageable with and disengageable from said studs whereby said arm may be locked to and released from said shaft for movement therewith and independent rearward movement, and means providing permanent pivotal connection between said shoe and the upper end of said spring and forward and rearward lost motion connection between said shoe and the upper end of said arm.

3. In an ironing machine, a roll and a cooperating shoe, a rockably mounted shoe operating shaft in back of and parallel with said roll adjacent the lower portion thereof, a shoe supporting arm comprising side flanges pivoted at their lower ends on said shaft and a back wall connecting said flanges, latching studs fixed to said shaft projecting outward therefrom adjacent the inner faces of said flanges restraining said arm against relative movement lengthwise of said shaft, a leaf spring fixed at its lower end to said back wall extending upward and forward therefrom between said flanges, a substantially U-shaped release lever pivoted on said flanges at the inner faces thereof straddling said spring and having downwardly and forwardly extending latch fingers engageable with and disengageable from said studs whereby said arm may be locked to and released from said shaft for movement therewith and independent rearward movement, and means providing permanent pivotal connection between said shoe and the upper end of said spring and rearward and forward lost motion connection between said shoe and the upper end of said arm, the upper portion of said wall being disposed for contact by said lever in the movement thereof in unlatching direction.

4. In an ironing machine, a roll and a cooperating shoe, a rockably mounted shoe operating shaft in back of said roll, a shoe supporting arm pivoted on said shaft, a release lever pivoted on said arm, said lever and shaft having cooperating latching elements such that forward movement of said lever relative to said arm positively locks

75

the latter to said shaft for movement therewith and rearward movement of said lever relative to said arm releases the latter from said shaft for rearward turning movement thereabout, said arm having an abutment disposed for contact by said release lever in the rearward movement thereof to releasing position, and operating connections between said arm and said shoe comprising a lost motion connection therebetween and yielding means carried by said arm effective for yieldingly urging said shoe toward said roll in the movement of said arm toward said roll.

5. In an ironing machine, a roll and a cooperating shoe, a rockably mounted shoe operating shaft in back of said roll, a shoe supporting arm pivoted on said shaft, a release lever mounted on said arm for movement therewith and for movement relative thereto, said lever and shaft having cooperating latching elements such that forward movement of said lever with said arm about said shaft positively locks said arm to said shaft for movement therewith and rearward pressure on said lever releases said arm from said shaft for rearward turning movement thereabout, said lever and arm having cooperating means for moving said arm rearward in the rearward movement of said lever after release of said arm from said shaft, and operating connections between said arm and said shoe, comprising a lost motion connection therebetween and yielding means carried by said arm effective for yieldingly urging said shoe toward said roll in the movement of said arm toward said roll.

6. In an ironing machine, a roll and a cooperating shoe, a rockably mounted shoe operating shaft in back of said roll turnable a predetermined distance forward and rearward for moving said shoe forward into cooperating pressure contact with and rearward away from said roll, a shoe supporting arm pivoted on said shaft, a release lever mounted on said arm for movement therewith and for movement relative thereto, said lever and shaft having cooperating latching elements such that engagement of said elements locks said arm to said shaft for movement therewith and rearward pressure on said lever disengages said latching elements and releases said arm from said shaft for rearward turning movement thereabout, said lever and arm having cooperating means for moving said arm rearward in the rearward movement of said lever after release of said arm from said shaft, and operating connections between said arm and said shoe comprising a lost motion connection therebetween and yielding means carried by said arm effective for yieldingly urging said shoe toward said roll in the movement of said arm toward said roll, the center of gravity of said shoe and arm being so disposed that said shoe will remain in position to said roll when said arm is unlatched from said shaft, said latching elements comprising a member on said arm yieldingly urged toward latching position and being so disposed as to be out of engagement when said arm is swung forward about said shaft into position with said shoe in contact with said roll when said shaft is in its forward position and engaged by turning of said shaft to its rearward position.

7. In an ironing machine, a roll and a cooperating shoe, a rockably mounted shoe operating shaft in back of said roll turnable a predetermined distance forward and rearward for moving said shoe forward into cooperating pressure contact with and rearward away from said roll, a shoe supporting arm pivoted on said shaft, a re-

lease lever pivoted on said arm having a latch finger overlying said shaft yieldingly urged toward the latter, said finger and shaft having cooperating latching elements such that engagement of said elements positively locks said arm to said shaft for movement therewith and rearward pressure on said lever disengages said latching elements and releases said arm from said shaft for rearward turning movement thereabout, said lever and arm having cooperating means for moving said arm rearward in the rearward movement of said lever after release of said arm from said shaft, and operating connections between said arm and said shoe comprising a lost motion connection therebetween and yielding means carried by said arm effective for yieldingly urging said shoe toward said roll in the movement of said arm toward said roll, the center of gravity of said shoe and arm being so disposed that said shoe will remain in position to said roll when said arm is unlatched from said shaft, said latching elements being so disposed as to be out of engagement when said arm is swung forward about said shaft into position with said shoe in contact with said roll when said shaft is in its forward position and said latching elements being engaged by turning of said shaft to its rearward position.

8. In an ironing machine, a roll and a cooperating shoe, a rockably mounted shoe operating shaft in back of said roll turnable a predetermined distance forward and rearward for moving said shoe forward into cooperating pressure contact with and rearward away from said roll, a shoe supporting arm pivoted on said shaft, a release lever pivoted on said arm having a latch finger overlying said shaft yieldingly urged toward the latter and provided with a notch in its lower edge, a latching stud fixed to said shaft engageable in said notch whereby said arm may be locked to said shaft for movement therewith and may be released from said shaft for movement thereabout, said lever and said arm having cooperating means for moving the latter rearward about said shaft with said lever, and operating connections between said arm and said shoe comprising a lost motion connection therebetween and yielding means carried by said arm effective for yieldingly urging said shoe toward said roll in the movement of said arm toward said roll, the center of gravity of said shoe and arm being so disposed that said shoe will remain in position to said roll when said arm is unlatched from said shaft, said notch and stud being so disposed as to be out of engagement when said arm is swung forward about said shaft into position with said shoe in contact with said roll when said shaft is in its forward position and engaged by turning of said shaft to its rearward position.

9. In an ironing machine, a roll and a cooperating shoe, a rockably mounted shoe operating shaft in back of said roll, a shoe supporting arm pivoted on said shaft, a latching stud fixed to said shaft, a release lever pivoted on said arm having a downwardly and forwardly extending latch finger having a notch engageable over and disengageable from said stud whereby said arm may be positively locked to and released from said shaft for movement with said shaft and independent thereof, said lever and arm having cooperating means for moving the latter rearward with said lever when said arm has been released from said shaft, and operating connections between said arm and said shoe comprising a lost

motion connection therebetween and yielding means carried by said arm effective for yieldingly urging said shoe toward said roll in the movement of said arm toward said roll.

5 10. In an ironing machine, a roll and a cooperating shoe, a rockably mounted shoe operating shaft in back of said roll, a shoe supporting arm pivoted on said shaft, a latching stud fixed to said shaft, a release lever pivoted on said arm having a downwardly and forwardly extending latch finger having a latching element engageable over and disengageable from said stud whereby said arm may be locked to and released from said shaft for movement therewith and independent thereof, means yieldingly urging said latch finger in latching direction said lever and arm having cooperating means for moving the latter rearward with said lever when said arm has been released from said shaft, and operating connections between said arm and said shoe comprising a lost motion connection therebetween and yielding means carried by said arm effective for yieldingly urging said shoe toward said roll in the movement of said arm toward said roll, the center of gravity of said shoe and arm being so disposed that said shoe will remain in position to said roll when said arm is unlatched from said shaft, said stud and said latching element being so disposed as to be out of engagement when said arm is swung forward about said shaft into position with said shoe in contact with said roll when said shaft is in its forward position and said latching elements being engaged by turning of said shaft to its rearward position.

35 11. In an ironing machine, a roll and a cooperating shoe, a rockably mounted shoe operating shaft in back of said roll turnable a predetermined distance forward and rearward for moving said shoe into pressure contact with and away from said roll, a shoe supporting arm pivoted on said shaft with operating connections to said shoe comprising a lost motion connection therebetween and yielding means carried by said arm effective for yieldingly urging said shoe toward said roll in the movement of said arm toward said roll, the center of gravity of said shoe and arm being so disposed that said shoe will remain in position to said roll when said arm is unlatched from said shaft, and means for positively locking said arm to said shaft for movement therewith and releasing it from said shaft for rearward movement thereabout, said means comprising latching elements out of engagement when said arm is turned about said shaft into position with said shoe in contact with said roll when said shaft is in its forward position and said latching elements being engaged by turning of said shaft to its rearward position.

FREDERICK M. FREIS.
